US00D476656S

(12) **United States Design Patent** (10) Patent No.: **US D476,656 S**
Swanson et al. (45) Date of Patent: ** Jul. 1, 2003

(54) **OPTICAL MARK READER HOUSING**

(75) Inventors: **Mark R. Swanson**, Wisconsin Rapids, WI (US); **Gary L. Friederichs**, Chilton, WI (US)

(73) Assignee: **Renaissance Learning, Inc.**, Wisconsin Rapids, WI (US)

(**) Term: **14 Years**

(21) Appl. No.: **29/147,777**

(22) Filed: **Sep. 4, 2001**

(51) LOC (7) Cl. **14-02**

(52) U.S. Cl. **D14/385**

(58) Field of Search D14/383, 385-387; 235/380, 382, 382.5; 434/355, 363, 353

(57) **CLAIM**

The ornamental design for an optical mark reader housing, as shown and described.

DESCRIPTION

FIG. 1 is a perspective view of an optical mark reader housing according to our new design;

FIG. 2 is a front elevation view of the optical mark reader housing depicted in FIG. 1;

FIG. 3 is a rear elevation view of the optical mark reader housing depicted in FIG. 1;

FIG. 4 is a right side elevation view of the optical mark reader housing depicted in FIG. 1;

FIG. 5 is a left side elevation view of the optical mark reader housing depicted in FIG. 1; and,

FIG. 6 is a top plan view of the optical mark reader housing depicted in FIG. 1.

The stipple shading in the drawings is not intended to show texture.

1 Claim, 6 Drawing Sheets
